UNITED STATES PATENT OFFICE

2,015,000

SAIL RIG FOR WATER CRAFT

Christian August Beringer, Berlin, Germany

Application August 19, 1933, Serial No. 685,897
In Germany September 17, 1932

8 Claims. (Cl. 114—90)

This invention relates to a rig for sailing craft especially for yachts. The invention has for its object to produce a rig which is easy to manipulate and allows of going near to the wind. For 5 this purpose, the mast is arranged with its heel approximately in the center between stem and stern and the sail area in front of the mast is subdivided into several sails, whose sail area in the position "near to the wind" in projection on the 10 midship plane is approximately equal to the sail area of the main sail.

An aerodynamic slot effect is obtained by subdividing the fore sail area.

There is also provided according to the invention an auxiliary mast, whose head is connected to the main mast and whose heel is arranged approximately in the center between the heel of the main mast and the stem.

The invention therefore consists in the combination of a main mast approximately in the center of the midship line and of an inclined auxiliary mast approximately in the center between the heel of the main mast and the tack of the foremost sail. The head of the auxiliary mast 20 lies close to the head of the main mast and is connected therewith. There are also provided according to the invention a main sail on the main mast and at least four fore sails having in projection on the midship plane approximately the 25 same sail area as the main sail.

Further features of the invention are obvious from the further description.

With reference to the accompanying drawing, the subject matter of the invention is shown by 35 way of example in side elevation.

There are provided in the sail rig according to the invention two masts A and B which are inclined towards each other; these masts carry the main sail with converging luff and leach and the 40 large foresail area which is multi-subdivided in proportion to the main sail. The head members c and d of the masts are connected by a bolt e after the manner of a jolly mast. The two masts are then so rigged that mast A carries the main 45 sail I and a fore sail III while there is arranged on the mast B on its aft edge a fore sail II (like a middle staysail) overlapping the fore sail III and in front at least a fore sail V or IV.

It is believed in view of the foregoing that a 50 further detailed description of the invention is unnecessary. Likewise it is believed that the advantages of the invention will be readily apparent.

Having thus fully described the invention what 55 is claimed as new and desired to be secured by Letters Patent is:

1. Rig for sailing craft especially for yachts, comprising in combination a main mast approximately in the center of the midship line, an inclined auxiliary mast approximately in the center between the heel of the main mast and the tack of the foremost sail, the head of the said auxiliary mast lying close to the head of the main mast and connected therewith, a main sail on the main mast and at least four fore sails having in projection on to the midship plane approximately 10 the same sail area as the main sail when the craft is going near to the wind.

2. Rig for sailing craft especially for yachts, comprising in combination, a main mast approximately in the center of the midship line, an inclined auxiliary mast approximately in the center between the heel of the main mast and the tack of the foremost sail, the head of the said auxiliary mast lying close to the head of the main mast and connected therewith, a triangular main 20 sail on the main mast and at least four fore sails having in projection on to the midship plane approximately the same sail area as the main sail when the craft is going near to the wind, the fore sails forming two groups, the front group being arranged substantially in front of the auxiliary mast and the rear group behind the auxiliary mast.

3. Rig for sailing craft especially for yachts, comprising in combination, a main mast approximately in the center of the midship line, an inclined auxiliary mast approximately in the center between the heel of the main mast and the tack of the foremost sail, the head of the said auxiliary mast lying close to the head of the main mast and connected therewith, a triangular main sail on the main mast and at least four fore sails having in projection on to the midship plane approximately the same sail area as the main sail when the craft is going near to the wind, the fore sails 40 forming two groups, the front group being arranged substantially in front of the auxiliary mast and the rear group behind the auxiliary mast, the foremost sail of each group extending upwardly approximately to the masthead.

4. Rig for sailing craft especially for yachts, comprising in combination, a main mast approximately in the center of the midship line, an inclined auxiliary mast approximately in the center between the heel of the main mast and the tack 50 of the foremost sail, the head of the said auxiliary mast lying close to the head of the main mast and connected therewith, a triangular main sail on the main mast and at least four fore sails having in projection on to the midship plane approx- 55

imately the same sail area as the main sail when the craft is going near to the wind, the fore sails forming two groups, the front group being arranged substantially in front of the auxiliary mast

5 and the rear group behind the auxiliary mast, the foremost sail of each group extending upwardly approximately to the masthead, the fore leech of the rear sails of each group being shorter than the fore leech of the front sails of each group.

10 5. Rig for sailing craft especially for yachts, comprising in combination, a main mast approximately in the center of the midship line, an inclined auxiliary mast approximately in the center between the heel of the main mast and the tack

15 of the foremost sail, the head of the said auxiliary mast lying close to the head of the main mast and connected therewith, a triangular main sail on the main mast and at least four fore sails having in projection on to the midship plane approximately the same sail area as the main

20 sail when the craft is going near to the wind, the fore sails forming two groups, the front group being arranged substantially in front of the auxiliary mast and the rear group behind the

25 auxiliary mast, the foremost sail of each group extending upwardly approximately to the masthead, the fore leech of the rear sails of each group being shorter than the fore leech of the front sails of each group, the sails of each group being relatively arranged so that the foremost sail of each

30 sail of each group overlaps at its aft leech the rear sails of the same group.

6. Rig for sailing craft especially for yachts, comprising in combination, a main mast approximately in the center of the midship line, an inclined auxiliary mast approximately in the center between the heel of the main mast and the tack

35 of the foremost sail, the head of the said auxiliary mast lying close to the head of the main mast and connected therewith, a triangular main sail on the main mast and at least four fore sails having in projection on to the midship plane approximately the same sail area as the main

40 sail when the craft is going near to the wind, the fore sails forming two groups, the front group being arranged substantially in front of the auxiliary mast and the rear group behind the auxiliary mast, the foremost sail of each group extending upwardly approximately to the masthead, the fore

45 leech of the rear sails of each group being shorter than the fore leech of the front sails of each group, and the clew of the rear sails of each group lying deeper than the clew of the front sails of each group.

5 relatively arranged so that the foremost sail of each group overlaps at its aft leech the rear sails of the same group, and also overlaps the foremost sail of the after group and the main sail.

7. Rig for sailing craft especially for yachts, comprising in combination, a main mast approximately in the center of the midship line, an inclined auxiliary mast approximately in the center between the heel of the main mast and the tack of the foremost sail, the head of the said auxiliary mast lying close to the head of the main mast and connected therewith, a triangular main sail on the main mast and at least four fore sails having in projection on to the midship plane approximately the same sail area as the main

15 sail when the craft is going near to the wind, the fore sails forming two groups, the front group being arranged substantially in front of the auxiliary mast and the rear group behind the auxiliary mast, the foremost sail of each group ex-

20 tending upwardly approximately to the masthead, the fore leech of the rear sails of each group being shorter than the fore leech of the front sails of each group, the sails of each group being relatively arranged so that the foremost sail of each

25 group overlaps at its aft leech the rear sails of the same group and extends over the after group and also the main sail.

8. Rig for sailing craft especially for yachts, comprising in combination, a main mast approximately in the center of the midship line, an inclined auxiliary mast approximately in the center between the heel of the main mast and the tack of the foremost sail, the head of the said auxiliary mast lying close to the head of the main mast and connected therewith, a triangular main sail on the main mast and at least four fore sails having in projection on to the midship plane approximately the same sail area as the main

30 sail when the craft is going near to the wind, the fore sails forming two groups, the front group being arranged substantially in front of the auxiliary mast and the rear group behind the auxiliary mast, the foremost sail of each group extending upwardly approximately to the masthead, the fore

35 leech of the rear sails of each group being shorter than the fore leech of the front sails of each group, and the clew of the rear sails of each group lying deeper than the clew of the front sails of each group.
